UNITED STATES PATENT OFFICE

2,664,820

HAND STAMP DEVICE

George T. Brown, Jr., Dayton, Ohio, assignor to
 The National Cash Register Company, Dayton,
 Ohio, a corporation of Maryland

Application July 7, 1950, Serial No. 172,487

4 Claims. (Cl. 101—405)

1

This invention relates to a hand stamp device having a single handle adapted to hold any one of a plurality of type members such as may be used in price marking systems.

For instance, in a grocery store where it is intended to mark several cartons of the same kind of canned food, one price type member is used over and over, only to be changed when cans requiring another price are to be marked.

To employ a separate handle for each type member, of which there may be a hundred in a set, involves added cost and bulkiness to the set. Moreover it is desirable to have handles of various lengths, a long handle being used for marking cans in the bottom layers of a carton and a short handle being used for marking the tops of cans on a shelf where the overhead distance to the next higher shelf is small.

This invention provides a hand stamp device employing a single handle for use with any one of a number of type members.

Another object of the invention is to provide a handle of two sections, said two sections, when coupled together, forming a long handle, and one of the sections forming a short handle.

Another object of the invention is to provide a clutch and release mechanism of novel design by which the type members are attached to and released from the handle.

With these and incidental objects in view, the invention includes certain novel features of construction and combinations of parts, a preferred form or embodiment of which is hereinafter described with reference to the drawing which accompanies and forms a part of this specification.

Of the drawing:

Fig. 1 is a vertical section through a handle with a type member attached, the type member and release mechanism being shown in full;

Fig. 2 is a view, partly in vertical section, showing a modified form of the invention wherein the handle is in two sections;

Fig. 3 is an elevation of the device of Fig. 2, and in addition shows how a type member is supported in a storage tray;

Fig. 4 is a plan view of a type member;

Fig. 5 is a vertical section of the type member of Fig. 4 on the line 5—5 thereof;

Fig. 6 is a bottom view of the type member of Figs. 4 and 5;

Fig. 7 is a broken vertical section of a modified form of the invention;

Fig. 8 shows the substance of Fig. 2 with the upper section of the handle removed;

2

Fig. 9 is the clutch portion of Fig. 8 rotated 90° on a vertical axis;

Fig. 10 is a plan view of a portion of a type member storage tray; and

Fig. 11 is the clutch portion of the substance of Fig. 7 rotated 90° on a vertical axis.

Referring to Figs. 1, 4, 5, 6, 9 and 10, there is provided a tubular handle portion 20 having in the lower end thereof a plug 21 having a conical axial bore 22. A radial hole in the plug 21 contains a spring 23 under compression behind a ball 24 which is thereby resiliently held partially protruding into the conical bore, but prevented from being pushed clear into the bore by a constriction of the inner end of the radial hole in which it moves.

The type members, typified by the 10¢ type member shown in Figs. 4, 5 and 6 each have a type character 25, preferably of ink-impregnated micro-porous resiliently vulcanized rubber contained in a cup-like holder 26 in which the type character is secured, said cap having a conical tenon 27 adapted to enter the conical bore of the handle. The tenon has a groove 28 into which

the ball 24 fits after having been pushed sidewise by the entering point of the tenon. This clutch construction permits the fastening of a type member to the handle by merely placing the handle over the tenon of the type member and pushing down on the handle to cause the tenon to enter the conical bore and be secured therein by the spring-pressed ball entering the groove. Inasmuch as the outer end of the conical bore is much larger in diameter than the apex of the tenon, the handle may be held in one hand and placed over the tenon of the selected type member in the box without any difficulty. No exact centering of the handle with respect to the type member is necessary as would be the case if the bore in the handle and the cooperating tenon were cylindrical. If the preferred porous resilient rubber type is used, pressure on the type character is to be avoided until a printing operation is performed and, therefore, the cup-shaped

holder 26 is provided with a shoulder 29 adapted to rest on the supporting counter-bored circumference of a receiving hole 30 (Fig. 3) in a storage tray 31 so that the type can not come in contact with the bottom of the hole even when the handle is being attached.

Referring to Fig. 1, a release device is provided in the handle for forcing out the type member from the clutching action of the ball. This releasing device consists of a shaft 32, within the tubular handle 20, topped by a finger push button

33 protruding from the upper end of the handle. A turned over edge 34 of the handle portion cooperates with shoulder 35 on the button to prevent withdrawal of shaft 32 upwardly. A compressed spring seated at its upper end against the bottom of button 33 and seated at its lower end on plug 21 resiliently holds shaft 32 at its upper limit of movement. The lower end of shaft 32 is equipped with a pin which extends into the upper end of the conical hole 22 and rests against the tip of the tenon of a type member attached to the handle portion. Inward movement of the shaft by pressure applied to the push button will eject the type member. In use the type member is placed in the associated hole of the storage tray (see Fig. 10) and released by pressure applied to the push button. This release is positive and the action of the ball on the sloped tip of the tenon tends to eject the type member with a snap action.

In a modified form of release mechanism, shown in Figs. 7 and 11, the plug 40 has a cylindrical bore except for the lower end, which is flared and the release shaft 41 has a cylindrical lower end 42 having an axial bore 43. The wall 25 of bore 43 has a tear-drop opening 44 through which a spring-pressed ball 45 protrudes. As shaft 41 is forced downwardly against the action of spring 46, by pressure being applied on push-button 47, the ball 45 is pushed into the radial 30 hole 48. The tenon 49 on type member 50 is cylindrical with a groove 51 therearound. On release movement of the shaft 41 the ball is forced out of the cylindrical bore 43 and the type member may drop out under the force of gravity, as in 35 this case neither is there a pin pushing on the end of the tenon nor does the ball stay in contact therewith as the wall of the axial bore 43 intervenes.

A pin 52 cooperates with an axial groove 53 of 40 shaft 41 preventing its turning with respect to tubular handle portion 40 preserving the alignment of the tear-drop hole 48 and ball 45.

The form of the invention shown in Fig. 2 has a lower portion which is the same as that of Fig. 1, except it is shorter and the top of the tube is tapered as at 55 to receive the flared skirt 56 of an extension tubular handle portion 57 which has an axially bored plug 58 through which passes a narrowed portion 59 of release shaft 60 which has at its lower end a button 61 nearly in contact with button 62 on the upper end of release shaft 63 of the lower portion. The upper end of release shaft 60 is provided with a button 64 and said shaft is kept in the up position wherein button 61 makes contact with plug 58 through the action of spring 65 extending between plug 58 and button 64. The lower handle 66 is provided with a pin 67 which cooperates with L-shaped slot 68 in the flared skirt of tubular handle portion 57 so the upper and lower parts may be locked together. Pressure applied on button 64, when the upper and lower parts are locked together, will cause button 64 to move downwardly, making contact with button 62 and pushing it inwardly to release the attached type member 70. The lower portion, shown in Fig. 8, operates by itself in the same manner as the longer device of Fig. 1.

While the forms of mechanism herein shown and described are admirably adapted to fulfill the objects primarily stated, it is to be understood that it is not intended to confine the invention to the forms or embodiments herein disclosed, for it is susceptible of embodiment in various other forms.

What is claimed is:

1. A type member including a cup in which a type character is held, a rim-like shoulder portion extending outwardly from the bottom of the cup so the type member may be suspended cup side down in a hole in a tray, which hole will receive the cup proper but not the rim-like shoulder, and said cup-shaped holder having a cone-shaped tenon extending outwardly from the bottom thereof, said tenon having a groove around it between the apex and base in a plane normal to the axis of the cone.

2. In combination, a type member having a cone-shaped tenon with a groove around the tenon between the apex and base of the cone and in a plane normal to the axis of the cone; and a handle by which the type member may be releasably held by the tenon, said handle having a holding means and a release member, the holding means being a spring-pressed ball protruding into a conical recess in one end of the handle into which recess the tenon fits, the conical tenon and recess enabling ready entry of the tenon into the recess, the ball being pushed aside while the tenon end is passing it and thereafter returning to project into the groove, and the release member being mounted in the handle so it may be shifted by an operator from an ineffective to an effective position and vice versa, said release member having an end portion which moves into the recess and cooperates with the tenon of a held type member when the release member moves from ineffective to effective position, releasing the type member, and said release member normally being held in ineffective position by a spring extending between the release member and the handle.

3. The device of claim 2 in which the release member strikes the apex of the cone-shaped tenon of a handle-held type member when the release member moves from ineffective to effective position, ejecting it from the handle.

4. The device of claim 2 in which there is provided an extension piece for the handle which may be attached to the handle to lengthen it, said extension piece having a shiftable releasing member, normally spring-held in ineffectual position, but which when shifted, while the extension is attached to the handle, shifts the release member held by the handle to release any type member held thereby.
